ELECTRIC ORGAN

Joseph Palma, Jr., Wheaton, Ill., assignor to Hammond
Organ Company, Chicago, Ill., a corporation of Dela-
ware

Filed Sept. 25, 1959, Ser. No. 57,688

Term of patent 14 years

(Cl. D56—2)

Fig. 1.

Fig. 3.

Fig. 2.

Fig. 1 is a perspective view of an electric organ, showing my new design;

Fig. 2 is a reduced side elevational view; and

Fig. 3 is a fragmentary sectional view thereof, taken along the line 3—3 of Fig. 1.

The top of the electric organ is plain and unornamented and the side not shown is substantially the same in appearance as the side shown.

I claim:

An ornamental design for an electric organ, as shown and described.
